CIGAR-MAKING MACHINE.

SPECIFICATION forming part of Letters Patent No. 636,981, dated November 14, 1899.

Application filed January 14, 1899. Serial No. 702,135. (No model.)

To all whom it may concern:

Be it known that I, FRÉDERIC HAEHNEL, mechanical engineer, a citizen of France, residing at Rue Dambrugge 104, Antwerp, in 5 the Kingdom of Belgium, have invented certain new and useful Improvements in Cigar-Making Machines, of which the following is a clear description.

This invention relates to cigar-making machines; and it consists in the improved machine of this nature substantially constructed as hereinafter described and finally embodied in the clauses of the claim.

I have fully illustrated the invention in the 15 accompanying drawings, wherein corresponding letters of reference indicate like parts, and wherein—

Figure 1 is a view in side elevation of my invention. Fig. 2 is a top plan view of my 20 improved cigar-making machine. Fig. 3 is a front view of the machine somewhat enlarged and certain portions thereof being removed. Fig. 4 is a longitudinal sectional view of the upper portion of the machine. Fig. 5 is a 25 perspective view of that portion of the mechanism of my machine whereby the cigars after being formed are successively projected into the molds for giving them finished shape. Fig. 6 is also a perspective view of the mechanism referred to in Fig. 5, the parts being 30 shown in the positions in which they act to project a cigar into its mold. Figs. 7 and 8 are respectively a side view and a top plan view of certain parts which act to maintain 35 the filler-feeding mechanism in its advanced position. Figs. 9 and 10 are side views of certain levers whereby motion is imparted from the drive-shaft of the machine to its several working parts. Figs. 11, 12, and 13 are 40 longitudinal sectional views of that portion of the machine whereby the rolling and wrapping of the cigars are effected, the three views showing a cigar at several stages of this operation; and Fig. 14 is a detail view of a portion 45 of the mechanism shown in Fig. 4.

The letter α in said drawings designates the frame of the machine, and upon it is mounted a top plate α' , said top plate supporting a pair of vertically-disposed parallel 50 plates α^2 , each having on its outer face a pair

of L-shaped flanges α^3 , forming a guideway α^4 . Above this pair of L-shaped flanges is another longitudinal and outwardly-projecting flange α^5 .

In the frame α , beneath the top plate α' , is 55 journaled the main shaft b of the machine, said shaft carrying at one end a gear-wheel b' , with which meshes a small pinion b^2 upon one end of a shaft b^3 , also journaled in said frame and carrying at its other end a belt- 60 pulley b^4 . The shaft b^3 is the drive-shaft.

Beneath the shaft b is arranged a stationary shaft c , the same providing a fulcrum for an inverted-T-shaped lever c' and for each of a pair of upwardly-extending levers c^2 . 65 The body or vertical portion of the lever c' is bifurcated, forming lugs, as at c^3 c^4 , and the levers c^2 are enlarged near their lower ends, and in the enlargement c^5 thus formed is a curved slot c^6 , which receives the shaft b . 70 Each lever c^2 is provided with an integral head c^7 , in which is formed an elongated slot c^8 , and in this slot works the trunnion d of a bracket d' , to which is secured a guide-piece d^2 , that works in the corresponding guide- 75 way a^4 .

The levers c' and c^2 are worked back and forth upon the shaft c by means of tappets d^3 d^4 , suitably disposed upon the shaft b , so as to secure the proper relative actuation of 80 the parts hereinafter described that are dependent upon these levers for their movement.

Upon the upper surface of the top plate α' and in a longitudinal recess e , formed therein, 85 is disposed an elongated carriage e' , in which are arranged the molds e^2 for receiving and completing the shaping of the cigars, the said molds being secured in position by means of a set-screw e^0 . The bottom of this carriage 90 is provided with a series of teeth or notches e^3 , with which the point of a pawl e^4 engages, the pawl being fulcrumed in a reciprocating block e^5 and having its idle end weighted, so as to keep its point in contact with the teeth 95 e^3 . From the block e^5 projects a spindle e^6 , having an adjusting-nut e^7 , about which is coiled a spiral spring e^8 , said spring bearing against the block at one of its ends and at the other of its ends against the end wall of 100

a casing e^9 , that is suspended from the top plate a^2 . It should be remarked that an opening e^{10} is formed in the top plate above the casing for the point of the pawl to work in. 5 The block e^5 is reciprocated by means of a pin e^{11} , adjustably mounted on a bar e^8 , connecting the levers c^2 , as said levers vibrate, each actuation of the block imparting through the pawl e^4 an advance movement to the carriage e' .

The rear portion f of each plate a^2 is elevated, and upon it is mounted a horizontal plate f' , that projects for a considerable distance rearwardly. This plate is provided 15 with two or more pairs of transversely-disposed slots f^2 , and upon it is mounted a pair of L-shaped strips f^3 , the same being adjustably secured in position relatively to each other by means of bolts f^4 , penetrating said 20 strips and the slots.

Above the plate f' is arranged a reciprocating carriage g , the under side of said carriage consisting of a plate g' , having a series of teeth or serrations g^2 , and said plate being 25 removably secured in any desirable manner to the carriage. The object of removably securing this plate to the carriage is to provide for the employment of various widths of this element which acts between the L-shaped 30 strips f^3 and which in its reciprocations and by virtue of its serrations coacts with the plate f' to advance the tobacco which is to form the filler.

Projecting upwardly from the plate f' and 35 both sides of the carriage g are two pairs of lugs h^1 , and connecting the members of each of these pairs of lugs is a rod h^2 . The rod h^2 , joining the lugs h^1 , is connected to a hook h^3 on the carriage by means of a helical 40 spring h^4 , which spring, it will be obvious, acts to draw the carriage rearwardly. Upon the top of the carriage is pivotally mounted a pair of horizontally-vibrating hooked pawls h^5 , the same working in opposite directions and 45 being adapted to engage lugs h^6 , projecting upwardly from the plate f' and having their idle ends drawn toward each other by means of a spiral connecting-spring h^8 , all as clearly shown in Figs. 4, 7, and 8.

50 The carriage g is adapted not only for reciprocation, but also for elevation, when actuated by pairs of bell-crank levers i , that are fulcrumed upon the rods h^2 . The corresponding arms of each pair of bell-crank levers i are 55 connected by rods i^1 i^2 , the rods i^1 working in horizontal slots i^3 in projections i^4 on the carriage. The rearmost bell-crank levers i have forwardly-projecting extensions j .

50 j^1 j^2 are pairs of guides that project upwardly from the flange a^3 at the forward end of each plate a^2 , being secured thereto by bolts j^3 . Between these guides works a rectangular frame j^4 , against the back of which is secured a knife or cutter j^6 , which is adapted to move downwardly in approximate contact with the forward edge of the plate f' , so as to intermittently cut off the wads of filling.

The frame has projecting outwardly from it and between the guides j^1 j^2 trunnions j^7 , with which engage levers k , that are fulcrumed 70 each side of the machine in and outside of the elevated portion f of each plate a^2 , said levers being provided with slots k^1 for the reception of the trunnions and being coactively operated from the levers c^2 by adjustable pitmen k^2 . The levers k are spaced from the sides of the frame j^4 by means of washers j^8 , and beneath said washers and bearing against them are the extensions j .

Upon the outer face of the rectangular frame j^4 is disposed a plate k^3 , said plate being held against the frame by means of springs k^4 , arranged on spindles k^5 , that penetrate slots k^6 in said plate and project from the plate forming the knife j^6 , the outer ends of 85 said spindles being provided with adjusting-nuts k^7 for the springs. As the frame j^4 reciprocates the movement of the plate k^3 is each time, both in the upward and in the downward movement, for an instant retarded 90 by the action of an outwardly-curving spring k^8 , which projects downwardly from a cross-piece k^9 , surmounting the guides j^1 j^2 , and bears against a contact-strip k^{10} , secured upon said plate. The plate k^3 , in other words, can 95 only move a distance corresponding to the length of its slots k^6 . The plate k^3 is made movable, so as to retract not only out of the way of the gate when the latter is closed, but also out of the way of the bar n^1 as the latter 100 moves forward to roll the cigar.

At the forward end of the plate f' and beneath the same is hinged a gate l , said gate being controlled by springs l^1 and being adapted to coact with the plate k^3 to prevent the tobacco from being fed out except when the frame descends to cut off the desired quantity of tobacco and at the same time push aside the gate to make a passage.

110 m is a belt or apron that is secured in a shaft m^1 , controlled by a ratchet and pawl m^0 and connecting the elevations f of the plates a^2 at one of its ends and which at its other end is removably secured in a suitable clamp m^2 , its middle portion being approximately 115 beneath the frame j^4 . This belt or apron passes over a table m^3 , which is disposed slightly in front of the side frame j^4 , its front and rear edges being preferably rounded off.

The brackets d^1 form bearings for the trunnions n of an ovoid bar n^1 , over which the belt or apron also passes and on which it is adapted to coact with the table m^3 as it moves to form a running pocket, in which the cigar is wrapped in an obvious manner. It should 120 be remarked that the front portions of the elevations f are cut away, as at n^2 , so as to permit the ovoid bar to be carried far enough rearwardly to get past the line of movement of the frame h^4 . One of the plates a^2 has an 125 inwardly-projecting flange n^3 , upon the top of which is adapted to wipe a lug n^4 , that projects from one of the trunnions of the ovoid bar, said lug thus acting to turn the bar back

130

out of its vertical position, so that it can best coact with the table m^3 to produce the running pocket in the belt or apron.

o designates a pair of levers, the forward end of each of which has a slot o' and the rear end of which is fulcrumed, as at o^2 , in the carriage g . The slot o' in each of these levers receives the corresponding trunnion of the ovoid bar n' , and just before the ovoid bar 10 approaches the forward limit of its movement the end of the slot in each of these levers is reached, and consequently the lever is drawn upon, which action imparts an advance movement to the carriage g .

15 At the points o^2 of pivotal connection for the rear ends of one of the levers o a pitman o^3 is connected, the free end of this pitman being connected to one end of a lever o^4 , which is fulcrumed upon one of a pair of shafts o^5 , journaled beneath the plate f' and carrying a belt o^6 , which initially feeds the tobacco filler onto the plate f' and beneath the carriage g . The lever o^4 carries a weighted pawl o^7 , which engages the teeth of a ratchet-wheel o^8 , secured upon one end of one of the rolls over which the belt o^6 passes. Just before the ovoid bar completes its forward movement the belt o^6 is simultaneously moved through the above mechanism.

30 One member of the clamp m^3 is formed as one portion of a feedway, whereby the wrapped cigars are successively projected into their respective molds, the other portion being movable around a shaft p , which is journaled in 35 lugs p' , that extend upwardly from the top plate between the plates a^2 . The stationary member p^2 and the movable member p^3 of this feedway have concavities in their adjacent faces conforming approximately to the outline of a cigar. Across the top of the member p^3 extends a bar p^4 , against the ends of which bear springs p^5 , that are secured at their lower ends in the plates a^2 , said springs thus tending to maintain the feedway normally 40 closed.

45 q is a plunger-rod connecting vertically-moving bars q' , the lower edges of said plunger-rod being beveled, so as to give it the shape of a wedge. This rod is adapted to 50 move downwardly between the members p^2 p^3 , forcing the wrapped cigar through the space between said members and into their molds. It is also adapted to be moved toward and against the upper end of the movable member p^3 , so as to previously open the feedway, so that the wrapped cigar can readily enter, the pushing aside of the rod q being effected by the advance of the ovoid bar which engages the bars q' , carrying said rod.

55 60 The lower ends of the bars q' are connected by a slot-and-bolt arrangement s to upwardly-projecting arms s' , said arms being mounted upon a bar s^2 , which the adjoining end of the T-shaped lever c' carries. The 65 bars q' are braced by a rod s^3 , and a spring s^4 connects a hook on the lever c' with a hook on said rod. An elastic frame is thus formed,

so that the action of the plunger-rod q is not made absolutely positive, and said plunger-rod q can yield so as not to damage the cigar. 70

The starting and stopping of the machine are effected by means of a treadle t , said treadle being connected through a series of levers t' with a sleeve t^2 , that is keyed upon the shaft b^3 , said sleeve constituting one member of a 75 clutch, of which the other member is the annular boss or hub b^3 of the pulley b^4 , which is loosely mounted on said shaft.

When the carriage e' , which supports the molds, has been advanced to such a position 80 that the last mold has been utilized, an alarm u , mounted on the under side of the top plate a' , is adapted to be actuated by any suitable detent on said carriage.

In describing the operation it will be 85 presupposed that the treadle t having been worked to effect an engagement of the clutch and a consequent starting of the rotation of the shaft and actuation of the levers c' and c^2 in an obvious manner said levers c^2 have 90 advanced and through the levers o have drawn forward the carriage g , so that its pawls h^6 engage the lugs h^7 and lock said carriage in this position. The serrations or teeth of the plate g' on the under side of said 95 carriage will therefore have advanced the tobacco constituting the filler under the frame j^4 . Thereupon the slotted end of the lever k will be depressed, this action being effected by the rocking of the lever c' and the consequent lifting of the pitman k^2 . The depression of the slotted ends of the levers k effects the lowering of the frame j^4 and of the knife j^6 , carried thereby, the frame and the knife coacting, the one to push open the gate l and 100 the other to cut off the projecting portion 105 of the filler, which thereupon falls into the pocket formed in the belt or apron m between the rear edge of the table m^3 and the ovoid bar m' . It should be here remarked 110 that the movements of the levers c^2 are comparatively quick, so that they return to their rear position before the frame j^4 falls. The frame j^4 , having deposited the cut-off portion 115 of the filler in the pocket of the belt or apron m , is thereupon lifted by the levers k , whose slotted ends are raised again. It should be 120 remarked that when the slotted ends of the levers were lowered the extensions j of the bell-crank levers i were also lowered, thus 125 moving said bell-crank levers about their fulcrums, which action of course raised the carriage g , thereby lifting the pawls h^6 above the lugs h^7 , so that they could snap out of engagement therewith and permit the resetting of the carriage under actuation of its spring h^4 . Before the cut-off portion of the filler drops into the pocket of the belt or apron m the attendant has placed in said pocket the wrapper for the cigar, and it is into this 130 wrapper, of course, that the filler, strictly speaking, falls. Thereupon the levers c^2 again begin to move forward, carrying with them the ovoid bar m' , which when it approaches

the rear end of the table m^3 is turned back upon its trunnions by virtue of the contact between its lug n^4 , wiping upon the flange n^3 . This action of the ovoid bar obviates an undue pressure upon the cigar. It will be seen that as the ovoid bar continues to advance it acts, as hereinbefore described, in connection with the table m^3 , to form a running loop or pocket in the apron m , thus effecting the wrapping of the cigar. As it approaches the limit of its forward movement the ovoid bar strikes against the upper ends of the rods q' , carrying the plunger-rod q , forcing said rods in such a way that the plunger-rod impinges against the movable member p^3 of the feedway, thus opening the latter for the reception of the wrapped cigar. The next action to which the cigar is subjected is that of being pushed or forced through the feedway by means of the plunger-rod q , which is forced downwardly through the feedway by the lowering of the rods q' , actuated initially from the lever c' .

The advance of the carriage e' and the operation of the belt o^6 have been already described, as has also the action of the plate k^3 and its accessory parts, which coact with the frame j^4 to prevent a premature escape of the filler.

It will be obvious that in order to regulate the belt or apron m so as to produce running pockets of varying dimensions, and thus altering the size of the cigars, the adjusting mechanism for the shaft m' , comprised in the ratchet-and-pawl arrangement m^0 , need only be manipulated.

Having thus fully described my invention, what I claim as new, and desire to secure by Letters Patent, is—

1. In a cigar-making machine, the combination, with the frame, of a filler-feeding mechanism consisting of a plate supported upon a portion of said frame, a spring-actuated carriage adapted to coact with said plate to advance the filler, and means for advancing said carriage against the action of its spring, substantially as described.

2. In a cigar-making machine, the combination, with the frame, of a filler-feeding mechanism consisting of a plate supported upon a portion of said frame, a spring-actuated carriage adapted to coact with said plate to advance the filler, means for advancing said carriage against the action of its spring, locking means for securing said carriage in its advanced position, and means for releasing said carriage, substantially as described.

3. In a cigar-making machine, the combination, with the frame, of a filler-feeding mechanism consisting of a plate supported upon a portion of said frame, a spring-actuated elevatory carriage adapted to coact with said plate to advance the filler, said carriage being provided with teeth or serrations adjacent the plate, means for advancing said carriage against the action of its spring, locking means for securing said carriage in its

advanced position, and means for elevating said carriage to release the same from its locking means, substantially as described. 70

4. In a cigar-making machine, the combination, with the frame, of a filler-feeding mechanism consisting of a plate supported upon a portion of said frame, a spring-actuated elevatory carriage adapted to coact with said plate to advance the filler, said carriage being provided with teeth or serrations adjacent the plate, means for advancing said carriage against the action of its spring, spring-actuated hook-pawls carried by said carriage, lugs projecting from said plate and adapted to be engaged by said pawls to secure the carriage in its advanced position, operatively - connected and suitably - fulcrumed bell-crank levers, said levers being operatively connected to said carriage, and means for actuating said levers to elevate the carriage and disengage the pawls from said lugs, substantially as described. 80 85

5. In a cigar-making machine, the combination, with the frame, of a filler-feeding mechanism consisting of a plate supported upon a portion of said frame, a spring-actuated elevatory carriage adapted to coact with said plate to advance the filler, said carriage being provided with teeth or serrations adjacent the plate, means for advancing said carriage against the action of its spring, spring-actuated hook-pawls carried by said carriage, lugs projecting from said plate and adapted to be engaged by said pawls to secure the carriage in its advanced position, operatively - connected and suitably - fulcrumed bell-crank levers, said levers being operatively connected to said carriage, a filler-cutting mechanism disposed at one end of said filler-feeding mechanism and adapted to reciprocate transversely thereof, means for actuating said filler-cutting mechanism, and an extension or extensions projecting from said bell-crank levers and operatively engaging said filler-cutting mechanism, substantially as described. 90 95 100 105

6. In a cigar-making machine, the combination, with the main frame, and with a filler-feeding mechanism mounted in said frame and comprising a plate, of a filler-cutting mechanism disposed at one end of said plate and consisting of a reciprocating frame movable transversely thereof, a knife or cutter carried by said frame, a spring-actuated gate disposed beneath said frame, a plate movably mounted on said frame and coacting therewith and with the gate to prevent the escape of the uncut filler, and means for reciprocating said frame, substantially as described. 115 120 125

7. In a cigar-making machine, the combination, with a filler-feeding mechanism, of a filler-cutting mechanism consisting of a reciprocating frame, a knife carried by said frame, a spring-actuated gate disposed beneath said frame, a plate carried by said frame and movable independently of and adapted to coact therewith and with the gate 130

to prevent the escape of the uncut filler, and a spring carried by said frame and bearing against the plate, substantially as described.

8. In a cigar-making machine, the combination, with the frame, of a filler-feeding mechanism, filler-cutting mechanism operatively disposed with reference to said feeding mechanism, means for operating said filler-cutting mechanism, a loose belt or apron extending beneath said filler-cutting mechanism, a table, a reciprocating bar, said belt or apron extending over said table and the bar and said bar being disposed parallel to and adapted to reciprocate above said table, and levers operatively connecting said bar and the filler-feeding mechanism, said bar being adapted to actuate said feeding mechanism through said levers, substantially as described.

20 9. In a cigar-making machine, the combination, with the frame, of a filler-feeding mechanism, filler-cutting mechanism operatively disposed with reference to said feeding mechanism, means for operating said filler-cutting mechanism, a loose belt or apron extending beneath said filler-cutting mechanism, a table, a reciprocating bar, said belt or apron extending over said table and the bar and said bar being disposed parallel to and adapted to reciprocate above said table, levers operatively connecting said bar and the filler-feeding mechanism, a feedway disposed adjacent said table and near the end thereof remote from said filler-cutting mechanism, said feedway comprising a movable member, and a plunger-rod movable into said feedway, said bar being adapted to actuate said plunger-rod and the movable member to partially open the feedway, substantially as described.

40 10. In a cigar-making machine, the combination, with the frame, of a wrapping mechanism consisting of a table, a bar disposed parallel to and movable over said table, a loose belt or apron extending over said table and the bar, a feedway disposed at one end of said table, said feedway comprising a movable spring-actuated member, a plunger-rod movable into said feedway, reciprocating rods carrying said plunger-rod and adapted to be engaged by said bar, and means for reciprocating said rods, substantially as described.

11. In a wrapping mechanism for cigar-making machines, the combination of a suitably-supported table, a loose belt or apron extending over said table, a pivoted bar having, transversely, the shape of an ovoid and

said belt or apron also extending over said bar and said bar being disposed parallel to and adapted to reciprocate above said table, a bar situated near and somewhat beneath, one edge of said table, and a lug carried by said ovoid bar and adapted to wipe upon said last-named bar, substantially as described.

12. In a cigar-making machine, the combination, with the frame, of a top plate comprised in said frame, vertically-disposed parallel plates mounted on said top plate and provided with guideways, a table disposed between said vertical plates, brackets movable in said guideways, a pivoted bar carried by said brackets, a loose belt or apron extending over said bar and the table, said bar being disposed transversely with reference to and adapted to reciprocate above said table, and means for reciprocating said brackets, substantially as described.

13. In a cigar-making machine, the combination, with the frame, of a wrapping mechanism arranged therein, a longitudinally-movable carriage disposed beneath said wrapping mechanism, a series of molds carried by said carriage, said carriage having teeth on its undersurface, a suitably-supported spring-actuated block, a pawl pivoted in said block and adapted to engage said teeth, and means for moving said block, substantially as described.

14. In a cigar-making machine, the combination, with the frame, of filler-feeding mechanism, filler-cutting mechanism, wrapping mechanism, a movable carriage operatively disposed with reference to said wrapping mechanism and carrying a set of molds, a tappet-carrying revoluble shaft, a suitably-fulcrumed bifurcated T-shaped lever adapted to be actuated by said tappet-carrying shaft, other suitably-fulcrumed levers adapted to be actuated by said tappet-carrying shaft, operative connecting means between said T-shaped lever and the filler-cutting mechanism, and operative connecting means between the other levers and the filler-feeding mechanism, the wrapping mechanism and said carriage, substantially as described.

In testimony that I claim the foregoing I have hereto set my hand this 24th day of December, 1898.

FRÉDÉRIC HAEHNEL.
